UNITED STATES PATENT OFFICE

158,236

VACUUM COFFEE MAKER

John B. Ward, Corning, N. Y., assignor to Corning
Glass Works, Corning, N. Y., a corporation of
New York

Application February 9, 1948, Serial No. 144,372

Term of patent 3½ years

(Cl. D44—26)

To all whom it may concern:

Be it known that I, John B. Ward, a citizen of the United States of America, residing in the city of Corning, county of Steuben, and State of New York, have invented a new, original, and ornamental Design for a Vacuum Coffee Maker, of which the following is a specification, reference being had to the accompanying drawing, forming a part thereof:

Fig. 1 is a side elevational view of a vacuum coffee maker showing my new design; and

Figs. 2 and 3 are top plan views of the upper and lower bowls respectively.

The dominant features of the design reside in the parts drawn in full lines as shown.

I claim:

The ornamental design for a vacuum coffee maker, as shown and described.

JOHN B. WARD.
